Attorney, Agent, or Firm—Dennis H. Lambert

[57] CLAIM

I claim the ornamental design for a fingernail polish bottle, as shown and described.

DESCRIPTION

FIG. 1 is a front, top and side perspective view of only one embodiment of the design of the present invention, representing a kangaroo.

FIG. 2 is a front view in elevation of the design of FIG. 1. FIG. 3 is a back view in elevation of the design of FIG. 1. FIG. 4 is a left side view in elevation of the design of FIG. 1, the side opposite being a mirror image thereof.

FIG. 5 is a top plan view of the design of FIG. 1; and, FIG. 6 is a bottom plan view of the design of FIG. 1.
